Primary Examiner — Andrew T Nemeth

(57) **CLAIM**

The ornamental design for a toy for an animal, as shown and described.

DESCRIPTION

FIG. 1 is a perspective view of a toy for an animal design showing my new design.

FIG. 2 is a front view of a toy for an animal.

FIG. 3 is a rear view of a toy for an animal.

FIG. 4 is a right side view of a toy for an animal.

FIG. 5 is a left side view of a toy for an animal.

FIG. 6 is a top view of a toy for an animal; and, FIG. 7 is a bottom view of a toy for an animal.

The broken lines throughout the drawing figures depict portions of the toy for an animal that form no part of the claimed design.

1 Claim, 7 Drawing Sheets
